Filed July 5, 1960, Ser. No. 61,250

Term of patent 14 years

(Cl. D87—3)

FIG. 1

FIG. 2

Figure 1 is a perspective view of a card case or similar article in closed condition showing my new design;

The dominant features of my design reside in the V-notched interior compartments in combination with the deep V-notched removable inserts therein.

I claim:

The ornamental design for a card case or similar article, as shown and described.
